TEMPERATURE CONTROLLING APPARATUS
FOR INTERNAL COMBUSTION ENGINES

Louis G. Hartdorn, Forest Hills, N. Y.

Application May 9, 1929, Serial No. 361,562

14 Claims. (Cl. 123—174)

My invention relates to shutter control for automobile radiators and has for an object to provide a novel arrangement whereby the shutters will be under direct and sole control of a 5 thermostat or like heat sensitive device while the engine of the automobile is running, but will be automatically cut off from such control as soon as the engine is stopped.

Another object of the invention is to employ 10 the power of an automobile engine to establish an operative relation between a thermostat and the shutters of a radiator, which relation is rendered inoperative when the engine is stopped.

A more specific object of the invention is to 15 use suction created by the engine to throw in a clutch which establishes said operative relation between the thermostat and shutters, and which clutch when thus thrown in will remain fixed despite variations of suction, but will release 20 and terminate such operative relation when the suction is reduced practically to zero.

The present invention is a variant of that 25 shown in my ccpending application, Serial No. 59,253, filed September 29, 1925 and since ma- 30 tured into Patent No. 1,775,344. In the specific embodiment illu-trated in said application, I 35 showed a fixed thermcstat and a connection be- 40 tween the thermostat and shutters comprising a pair of relatively movable members which were 45 locked in fixed relative position by a clutch con- 50 trolled by the suction of the engine. In the pres- 55 ent invention, I provide a substantially fixed con- 60 nection between the thermostat and shutters but the thermostat is in a floating condition and is 65 unable to control the shutters so long as the en- 70 gine is not running. However, when the engine 75 is started I employ the pcwer of the engine (preferably in the form of suction) to establish 80 the thermostat in fixed operative position, and 85 I use a clutch to maintain the thermostat in 90 such position as long as the engine is running.

Another object of my invention is to provide 95 an improved clutch mechanism for use in the control of radiator shutters.

Another object of the invention is to provide 100 a very neat and compact arrangement in which the clutch mechanism and means for operating the same are contained mainly within the radi- 105 ator.

Another object of the invention is to provide 110 means for locking the clutch mechanism so as to prevent engine control of the shutters in sum- 115 mer time.

Other objects and advantages of the invention 120 will appear in the following description of a pre-

ferred embodiment and thereafter the novelty and scope of the invention will be pointed out in the claims.

In the accompanying drawing;

Figure 1 is a fragmentary view, in horizontal 5 section, of an automobile radiator and shutter mechanism showing my improved thermostatic control applied thereto;

Fig. 2 is a view, in longitudinal section, of the 10 clutch and controlling mechanism therefor, the section being taken on the line 2—2 of Fig. 1 and showing the parts on an enlarged scale;

Fig. 3 is a transverse section taken on the line 15 3—3 of Fig. 2;

Fig. 4 is a view in transverse section taken 20 on the line 4—4 of Fig. 2;

Fig. 5 is a skeleton view, in perspective, of the shutter controlling mechanism; and

Fig. 6 is a view in section, of a detail, the section being taken on the line 6—6 of Fig. 3. 25

The drawing shows my invention as applied to a radiator equipped with vertical shutters, in other words, the shutter vanes turn about a vertical axis. A section of a radiator is indicated at 10 in Fig. 1 and is provided with a shell 11 25 projecting on the forward side thereof. The shutter vanes 12 are pivoted at the top and bottom in core frame members 13. Only one of these members is shown in the drawing, but it will be understood that there is a core member 30 13 at the top and bottom of the radiator shell and the vanes have vertical pivot pins 14 journaled in these frame members. The shutter vanes are also pivotally connected at points 15 to an operating bar 16. A spring 17 connected 35 at one end to a core frame member 13 and to the other end to the bar 16, serves to hold the shutters normally in the closed position shown in Fig. 1.

The radiator 10 is formed near its upper end 40 with a tubular chamber 18 extending there- 45 through and adapted to receive a thermostat 19 for operating the shutters. The thermostat may be of any suitable type. As illustrated it con- 50 sists of a series of disc shaped chambers filled with expansive fluid which will cause the ther- 55 mostat to expand when the heat applied thereto reaches a predetermined degree. The outer end of the thermostat is connected by a link 20 to one arm of a bell crank 21, the other arm of 60 which is connected by the rod 22 to one end of the bar 16. The bell crank is journaled on a suitable support 23 secured to the outer face of the radiator. The inner end of the thermo- 65 stat bears against a plate 24 which serves as an 70 75 80 85 90 95 100 105 110 115 120 125 130 135 140 145 150 155 160 165 170 175 180 185 190 195 200 205 210 215 220 abutment therefor whereby, when the thermostat expands, it will rock the bell crank on its axis and move the bar 16 laterally, thereby swinging the shutter vanes to open position. However, the abutment 24 is fixed only when the engine is operating and consequently the thermostat cannot open the shutters or hold the shutters open no matter how hot the radiator may be when the engine stops running.

10 The plate 24 is secured to a tubular stem 25 which slides in a fixed bearing 26. A flange 27, at the inner end of the tubular stem engages the inner end of the bearing to limit outward sliding movement of the stem.

15 Secured to the inner face of the radiator and closing the inner end of the tubular chamber 18 is a plate 28 which carries a cylinder 29 projecting away from the radiator. This cylinder is open at its outer end but is closed at its inner end by the plate 28. A piston 30 is adapted to slide in the cylinder, this piston is provided with an annular outwardly cupped packing ring 31 which is normally pressed against the wall of the cylinder by a spring 32 supported in an annular flange member 33.

20 The piston 30 is of U-shape in axial section and telescopes over a cylindrical boss 34 projecting from the plate 28. However, there is sufficient clearance between the piston and said boss to receive a coil spring 35. One end of the spring bears against the plate 28 and the other against the piston 30, tending to force the piston outward or toward the right, as viewed in Fig. 2.

25 Secured to the piston 30 by means of a strap 36 is a pin 37 which enters the tubular stem 25. The boss 34 is hollow and forms a recess 38 in the plate 28 into which recess the stem 25 and the pin 37 may enter when in retracted position. The strap 36 is in the form of a loop connected at its center to the pin 37 and at each end to the piston 30. Each leg of the strap, after passing the flange 27 of the stem 25, is bent inward or toward the plate 24, so as to clear the plate 28 and enter the recess 38 when the parts are in retracted position. Thereafter, each leg is bent parallel to the plate 28 and then at right angles thereto, passing through a slot 39 in the plate 28 just outside of the cylinder 29. After passing the outer end of the cylinder each strap leg is bent at right angles toward the piston to which it is secured at the point 40.

30 The bearing 26 is supported by a spider 41 which is formed with a pair of legs 42. These legs project radially from the spider and at substantially right angles to the legs of the strap 36 and are then bent outward and pass through slots 43 in the plate 28. The legs are then bent to form feet 44 which are secured to the plate 28 by means of bolts 45. These bolts, as shown best in Fig. 6, are fixed in the plate 28 and are provided with nuts 46 which bear on opposite sides of the feet 44 and which may be adjusted to vary the position of the bearing 26, as desired.

35 Fitted to slide within the tubular stem is a sleeve 47. This sleeve is closed at one end by means of a head 48 threaded thereon. The pin 37 enters the sleeve 47 and is provided with a head 49 which slides freely within the sleeve 47 but which is prevented from being withdrawn therefrom by annular shoulders 50 formed on the sleeve. In other words, as the pin is moved

in and out by movement of the piston there is a lost motion between said pin and the sleeve.

40 The outer surface of the sleeve 47 is adapted to engage balls 51 fitted in the holes 52 in the tubular stem 25. As shown clearly in Fig. 2, the outer surface of the sleeve is stepped, having one long step 53 of reduced diameter and a short step 54 of slightly larger diameter. However, the balls 51 are of such diameter that they are at all times retained in the holes 52. When the balls are engaged by the step 54 they are forced outward and project into an annular recess 55 formed in the bearing 26. The stem 25 is then locked against sliding movement in the bearing 26 by engagement of the balls 51 with the inner end wall of the recess 55 (the wall at the right hand end, as viewed in Fig. 2). When the sleeve has been retracted or moved toward the right, in Fig. 2, so that the step 54 will clear the balls the latter may then move inward upon the step 53 and out of engagement with the recess 55, thereby unlocking or declutching the tubular stem 25 from the bearing 26. A spring 56 is fitted between the spider 41 and the flange 27 which tends to move the stem 25 toward the right, as viewed in Fig. 2, whenever such movement is permitted by retraction of the sleeve 47.

45 A tube 57 connects the working chamber of the cylinder with the intake manifold of the engine of the automobile or with any other part which will produce suction when the engine is operated, and hence when the engine operates and suction is produced in the cylinder 29, the piston 30 will be moved against the pressure of spring 35 to the position shown in Fig. 2. When, however, the suction is relieved, the piston will be moved by the spring 35, outward or toward the right, as viewed in Fig. 2.

50 One leg of the strap 36 is formed with a slot 40 which is engaged by a bolt 58 projecting from the cylinder and on this bolt are a pair of nuts 60 which may be adjusted to clamp the strap to the cylinder, so as to prevent movement of the piston and thus render the device inoperative.

The operation of the apparatus is, as follows:

55 Figures 1 and 2 show the abutment 24 in its extended position, that is, in the position to hold the thermostat in operative relation to the shutter. This position is assumed as soon as the engine is started, for during the first few strokes of the engine sufficient suction will be produced to draw the piston into the position shown in Fig. 2, thereby forcing the pin 37 toward the left, pushing the abutment 24 in the same direction by engagement of the strap 36 with the flange 27, and at the same time the head 49 of the pin 37 by engaging the head 48 of the sleeve 47 will force the latter forward to such position that the step 54 will force the balls 51 outward into engagement with the recess 55 of the bearing 26. This done, the abutment 24 will be maintained in its position despite variations of suction in the cylinder. In other words, the piston may move back and forth in the cylinder in response to variations of suction without in the least affecting the position of the abutment 24 because the pin 37 will merely slide back and forth within the sleeve 47 without moving the latter, and the balls 51 being pressed outward into the recess in the bearing 26 will prevent the stem 25 from being retracted by the spring 56.

60 While in this operative position the thermostat, when heated sufficiently, will operate the shut-

ter vanes in the usual manner, opening them in accordance with the heat developed in the radiator. The opening of the shutters is resisted by the spring 17 so that as the thermostat contracts, the shutters will correspondingly close. Thus, as long as the engine is running the shutters will be under direct control of the thermostat, but as soon as the engine stops running, the suction will cease and the air in the cylinder 29 will be restored to atmospheric pressure, permitting the piston to move outward under action of the spring 35 and retract the pin 37. As the latter nears its extreme retracted position the head 49 will engage the shoulders 50 on the sleeve 47 and will withdraw the step 54 from the balls 51, permitting the balls to move radially inward and the spring 56 to retract the stem 25. The plate or abutment 24 is thus retracted and even though the thermostat might have been holding the shutters wide open previous to the stoppage of the engine, the shutters would now be closed immediately by the action of the spring 17. Thus, the heat in the radiator will be conserved and will be available to prevent excessive cooling or freezing of the radiator and also to assist in restarting the engine.

In the summer time it is desirable to keep the shutters under thermostatic control and at such time it is not desirable to have the clutch mechanism operate. The piston 39 may, therefore, be locked against action by adjusting the nuts 68 to clamp the strap 36 to the cylinder 29 with the abutment 24 in advanced position shown in Fig. 2.

It will be observed that I have provided a very compact arrangement for controlling the position of the thermostat and that the mechanism is largely confined within the radiator with only a portion thereof projecting from the rear of the radiator.

While I have shown a preferred embodiment of my invention I reserve the right to make such changes in construction and arrangements of parts as fall within the spirit and scope of the following claims.

I claim:

1. In combination with an engine, a thermostat, a temperature control device for the engine, a connection between the thermostat and the device, a backing against which the thermostat may react to operate said device, means actuated by the engine for moving said backing against and away from said thermostat, and means for positively locking the backing in advanced position against the thermostat.

2. In combination, a thermostat, a temperature control device, a connection between the thermostat and the device, a backing against which the thermostat may react to operate said device, suction means for moving said backing against said thermostat, and resilient means for holding said backing normally in retracted position.

3. In combination with an engine and a shutter therefor, heat responsive mechanism connected with the shutter for operating the same, a thrust member against which said mechanism may react to operate the shutter, means normally holding said member retracted, and means actuated by the engine for advancing said member to render said mechanism operative.

4. In combination with an engine and a shutter therefor, heat responsive mechanism connected with the shutter for operating the same, a thrust member against which said mechanism may react to operate the shutter, means normally holding said member retracted, and suction means

responsive to the running condition of the engine for advancing said member to render said mechanism operative.

5. In combination with an engine radiator and a shutter therefor, a thermostat connected with said shutter, a member against which said thermostat may react to operate the shutter, said member being normally not fixed, and suction means for establishing said member in fixed relation to the thermostat.

6. In combination with an engine and shutters therefor, a thermostat connected with said shutters, a backing against which said thermostat may react to operate said shutters, said backing being normally not fixed, and means controlled by the power of the engine for establishing the backing in fixed relation to the thermostat whereby the thermostat may operate said shutters.

7. In combination with an engine and shutters therefor, a thermostat connected with said shutters, a backing for said thermostat, said backing being normally not fixed, and suction means responsive to the running condition of the engine for establishing the backing in fixed relation to the thermostat, whereby the thermostat reacts against the backing to operate said shutters.

8. In combination with an engine and shutters therefor, a thermostat connected with the shutters, a movable backing for said thermostat, means normally holding said backing in inactive position, means controlled by the engine for advancing the backing to such position that the thermostat may react thereagainst to operate said shutters, and means responsive to the running condition of the engine for locking the backing in said position as long as the engine is running.

9. In combination with an engine and shutters therefor, a thermostat connected with the shutters, a movable backing for said thermostat, means normally holding said backing in inactive position, means controlled by the engine for advancing the backing to such position that the thermostat may react thereagainst to operate said shutters, a clutch for holding the backing in advanced position, and means for releasing said clutch when the engine stops running.

10. In combination with an engine and shutters therefor, a thermostat connected with the shutters, a movable backing for said thermostat, means normally holding said backing in inactive position, means controlled by the engine for advancing the backing to such position that the thermostat may react thereagainst to operate said shutters, means responsive to the running condition of the engine for locking the backing in said position as long as the engine is running, and means for adjusting said position.

11. The combination with an engine, a radiator therefor, shutters for said radiator and a spring normally holding the shutters closed, the radiator having a chamber therein, of a thermostat in said chamber, a connection from one end of the thermostat to the shutters, a movable thrust member in said chamber, and means operated by the engine for advancing the thrust member against the other end of the thermostat to provide a backing against which the thermostat may react to open the shutters in response to temperature conditions of the radiator.

12. In combination with an engine, a radiator therefor, shutters for said radiator and a spring normally holding the shutters closed, the radiator having a chamber therein, of a thermostat

in said chamber, a connection from one end of the thermostat to the shutters, a movable thrust member in said chamber, means operated by the engine for advancing the thrust member against the other end of the thermostat to provide a backing against which the thermostat may react to open the shutters in response to temperature conditions of the radiator.

13. In combination with an engine, a radiator therefor, shutters for said radiator and a spring normally holding the shutters closed, the radiator having a chamber therein, of a thermostat in said chamber, a connection from one end of the thermostat to the shutters, a movable thrust member in said chamber, means operated by the engine for advancing the thrust member against the other end of the thermostat to provide a backing against which the thermostat may react

to open the shutters in response to temperature conditions of the radiator, a clutch for holding the thrust member in advanced position, and means for releasing the clutch when the engine stops running, said clutch and said releasing means being also contained within said chamber. 5

14. In combination, a thermostat, a temperature control device, a connection between the thermostat and said device, a backing against which the thermostat may react to operate said device, suction means for moving said backing against said thermostat, resilient means for holding said backing normally in retracted position, and manually operable means for preventing retraction of said backing after the backing has 10 been moved against said thermostat. 15

LOUIS G. HARTDORN.
